DESIGN FOR A CUFF LINK

Gloria Le Vaggi, Attleboro, Mass., assignor to
Swank, Inc., a corporation of Delaware

Application December 30, 1948, Serial No. 150,461

Term of patent 14 years

(Cl. D17—7)

To all whom it may concern:

Be it known that I, Gloria Le Vaggi, a citizen of the United States of America, residing at Attleboro, county of Bristol, State of Massachusetts, having invented a new, original, and ornamental Design for a Cuff Link, of which the following is a specification, reference being had to the accompanying drawing, forming a part thereof.

Fig. 1 is a top plan view showing my new design for a cuff link.

Fig. 2 is a side elevation and Fig. 3 is an end view thereof.

The dominant part of the design is shown in full lines.

I claim:

The ornamental design for a cuff link, substantially as shown and described.

GLORIA LE VAGGI.
